(57) **CLAIM**

The ornamental design for a protective speaker screen, as shown and described.

DESCRIPTION

FIG. 1 is a perspective view of the front of a protective speaker screen according to a first embodiment of my design;

FIG. 2 is a perspective view of the rear of the protective speaker screen shown in FIG. 1;

FIG. 3 is a front elevation of the protective speaker screen shown in FIGS. 1 and 2;

FIG. 4 is a rear elevation of the protective speaker screen shown in FIGS. 1-3;

FIG. 5 is a right cross-sectional elevation view of a protective speaker screen shown in FIGS. 1 through 4 taken along line 5-5 of FIG. 3 thereof;

FIG. 6 is a left cross-sectional elevation of a protective speaker screen shown in FIGS. 1 through 5 taken along line 6-6 of FIG. 3 thereof;

FIG. 7 is a bottom cross-sectional elevation of a protective speaker screen shown in FIGS. 1 through 6 taken along line 7-7 of FIG. 3 thereof;

FIG. 8 is a top cross-sectional elevation of a protective speaker screen shown in FIGS. 1 through 7 taken along line 8-8 of FIG. 3 thereof;

FIG. 9 is a perspective view of the front of a protective speaker screen according to a second embodiment of my design;

FIG. 10 is a perspective view of the rear of the protective speaker screen shown in FIG. 9;

FIG. 11 is a front elevation of the protective speaker screen shown in FIGS. 9 and 10;

FIG. 12 is a rear elevation of the protective speaker screen shown in FIGS. 9-11;

FIG. 13 is a right cross-sectional elevation of a protective speaker screen shown in FIGS. 9 through 12 taken along line 13-13 of FIG. 11 thereof;

FIG. 14 is a left cross-sectional elevation of a protective speaker screen shown in FIGS. 9 through 13 taken along line 14-14 of FIG. 11 thereof;

FIG. 15 is a bottom cross-sectional elevation of a protective speaker screen shown in FIG. 9 through 14 taken along line 15-15 of FIG. 11 thereof; and,

FIG. 16 is a top cross-sectional elevation of a protective speaker screen shown in FIGS. 9 through 15 taken along line 16-16 of FIG. 11 thereof.

The broken lines are directed to environmental features, which are shown for illustrative purposes only and form no part of the claimed design.
